(57) **CLAIM**

The ornamental design for a wireless microphone as shown and described.

DESCRIPTION

FIG. 1 is a bottom view of a wireless microphone showing the new design;

FIG. 2 is a front elevational view thereof;

FIG. 3 is a left elevational view thereof;

FIG. 4 is a partial enlarged view of no. 10, taken from FIG. 6 thereof;

FIG. 5 is a front perspective view thereof;

FIG. 6 is a rear perspective view thereof;

FIG. 7 is a rear perspective view thereof;

FIG. 8 is a rear elevational view thereof;

FIG. 9 is a right side elevational view thereof; and,

FIG. 10 is a top view thereof.

The broken line depict portions of the wireless microphone that form no part of the claimed design; the dot dash broken lines encircling a portion of the wireless microphone in FIG. 6 and illustrated in the enlarged view of FIG. 4, form no part of the claimed design.

1 Claim, 10 Drawing Sheets
